MOP

Henry L. Sweitz, Chicago, Ill.

Application February 8, 1943, Serial No. 475,063

7 Claims. (Cl. 15—229)

This invention relates to mops and particularly to those having the strings, or other means affording the desired absorbent body, extended from a relatively long and thin transverse head carried at the lower end of the mop handle.

Mops of the aforesaid character as heretofore constructed have, of course, included the elongated handle made from wood or the like, the broad and flat mass of strings or the like making up the water absorbing structure or body, and a clamping or securing means whereby the absorbent body was secured in place and held in the proper form on the lower end of the handle. In some instances such securing means has constituted a pair of opposed clamp elements carried permanently on the lower end of the handle and adapted to be clamped over the upper end of the absorbent body, while in other instances such securing means has included a transverse bar secured within the upper end of the absorbent body and having a socket or other securing means extended upwardly therefrom for connection with the handle. Such connecting means have invariably been made for metal in prior mops and have been considered to be essential in order to afford a lateral distribution of the strings, strands, or other material of the absorbent body. In other words, it has been considered desirable to provide a mass of strings or other absorbent material which is relatively thin and which is extended for a considerable distance laterally in both directions from the axis of the handle. Thus, in order to support such a wide and thin mass of absorbent strings or the like in a predetermined relation upon the handle, resort has been had heretofore to connecting means such as that hereinbefore described, and since the several elements of such connecting means have been made from metal, such prior constructions have involved excessive material and manufacturing costs. Moreover, it is well known that where such parts of the connecting means have been made from steel, the resulting mops have been unsuitable for use about highly finished woodwork or furniture or in those locations, such as in factories or store houses, where explosives are manufactured, processed or stored.

In view of the foregoing it is an important object of this invention to enable the cost of mops of the kind to which this invention relates to be materially reduced; to enable this to be done without the use of metal parts; to enable a wide and relatively thin head to be afforded

on the upper end of the absorbent body of strings, strands or the like solely through the use of textile fabric stitched with thread; to enable such a fabric head to embody substantial resistance to bending; and to enable such a fabric head to embody a socket formed from fabric and into which the lower end of a rod-like mop handle may be inserted.

It is recognized of course that the wide and thin head of a mop should remain in substantially a predetermined relation to the mop handle during use of the mop, and a further object of this invention is to enable this to be accomplished in a simple and expeditious manner 10 where the head of the mop as well as the securing means are made by forming and stitching of textile fabric. Further objects related to the foregoing are to enable a fabric mop head and the associated fabric securing means to be so 15 constructed and so related to the mop handle that the textile fabric cooperates with the mass of strings, strands or other absorbent material to maintain the desired wide and thin transverse form of the mophead; to enable these cooperating portions of the fabric and the absorbent body to cooperate with the handle in maintaining the head of the mop in the desired relation to the handle during use of the mop; and to 20 enable such a wide and thin mophead to be 25 constructed and secured in place on the handle through means which are wholly nonmetallic in character.

Other and further objects of the present invention will be apparent from the following description and claims and are illustrated in the accompanying drawing which, by way of illustration, shows preferred embodiments and the principle thereof and what I now consider to be 30 the best mode in which I have contemplated applying that principle. Other embodiments of the invention embodying the same or equivalent principle may be used and structural changes 35 may be made as desired by those skilled in the art without departing from the present invention and the purview of the appended claims.

In the drawing:

Fig. 1 is a front elevational view of a mop embodying the features of the invention;

Fig. 2 is a fragmental sectional view taken on an enlarged scale along the line 2—2 of Fig. 1;

Fig. 3 is an enlarged fragmental sectional view taken along the line 3—3 of Fig. 1;

Fig. 4 is an enlarged fragmental elevational

view similar to Fig. 1 and illustrating an alternative embodiment of the invention; and

Fig. 5 is a fragmental side elevational view taken from the line 5—5 in Fig. 4.

In the form chosen for disclosure herein the invention is embodied in a mop having a rod-like handle 10 made from wood or like material with a mophead 11 at its lower end which serves to support an elongated body 12 of absorbent material such as cotton strings, strands or the like. The absorbent body 12 is relatively wide and thin as will be evident from a comparison of Figs. 1 and 2 of the drawing, and the head 11 is arranged to support and maintain the upper end of the absorbent body 12 in this relatively wide and thin form. In accordance with the present invention this purpose is attained through means which are wholly nonmetallic in character, thereby adapting the mop of the present invention for use in locations where the presence of metal and particularly of steel is considered to be objectionable. Thus the head 11 is formed from two sheets or layers 14 of relatively heavy textile fabric, as indicated in Fig. 2, and these layers 14 of fabric are so formed and associated with the upper end of the absorbent body 12 that the upper end portion of the body 12 is held in the proper wide and thin form and in position on the lower end of the handle 10. In accomplishing this function the two layers 14 of fabric are disposed respectively on opposite or against faces of the upper end of the absorbent body 12 and the absorbent body is connected to the fabric by a plurality of spaced parallel rows 16 of stitching extended transversely with respect to the absorbent body and extending through the two layers of fabric and the intermediate portion of the absorbent body 12. The two layers 14 of fabric are also formed to afford means for connecting the head 11 to the lower end of the handle and this object is attained by forming the layers 14 of fabric to afford an upwardly facing socket 18 into which the lower end of the handle 10 may be extended.

In practice the two layers or pieces 14 of fabric are secured together about their side edges prior to the mounting of the absorbent body 12 between the two layers, and to this end the two layers 14 are cut to substantially the form shown in elevation in Fig. 1, there being, however, extended edges along the side thereof to afford material whereby internal seams may be formed to connect the two layers or pieces 14 together. The two pieces of material, or blanks, which are thus provided also have extended portions at the upper and lower edges thereof so that inturned hems 20 may be formed along the lower edges of the pieces 14 of material. The line of stitching which is utilized in forming each upper hem 20 is indicated at 20' in Fig. 1, while the line of stitching utilized in forming each of the lower hems 22 is indicated at 22' in Figs. 1 and 2. After the hems 20 and 22 have been formed along the upper and lower edges respectively of the two pieces 14 of fabric, these pieces are placed face to face with the hems on the outer faces thereof, and the side edges of the two pieces 14 of fabric are sewed together along lines of stitching 24, Fig. 3, to thereby form what will eventually be internal seams, the assembly formed by the two pieces 14 of fabric at this time being what may be termed an inside-out-relationship.

The fabric assembly which is thus formed is then turned to its right-side-out relationship so

that it is in condition for the mounting of the upper end of the absorbent body 12 therein. In the present case the absorbent body is illustrated as being formed by folding a mass of elongated cotton strings or the like at their midpoints so that the folded portions of the strings define the upper edge of the absorbent body. It will be evident, of course, that such folding is a mere matter of convenience, for in some instances the strings might be made shorter, and the ends of the strings may in such an instance define the upper edge of the absorbent body 12. In any event, the upper edge of the absorbent body is inserted into the relatively narrow, downwardly facing pocket defined between the two lower hems 22 so that the upper edge of the absorbent body 12 is engaged with the upper limits of the receiving pocket along the upper line of the pocket, as indicated at 11' in Fig. 1. The two layers of fabric which form the opposite sides of the pocket are then pressed together, as beneath the presser foot of a sewing machine, and the several spaced lines 16 of stitching are put in place. While the surfaces of the fabric pieces 14 at and between the lines 16 of stitching are in the present instance shown as being relatively flat, it will be recognized that in most instances the thread tension used in the making of the lines 16 of stitching will be such as to produce a quilting effect with a slight bulging between the lines 16 of stitching. With this arrangement the compressed mass of strings or other absorbent material between the lines 16 of stitching serves to space the connected layers 14 of fabric apart and to cooperate therewith in imparting a reasonable degree of rigidity to the head 11 of the mop. It will be understood, of course, that the head 11, in the region of the stitching 16, may be bent to a slight degree in use, but this is not objectionable.

When the sewing of the fabric has been completed, the socket 18, being formed from fabric, is relatively bendable back and forth, that is to the right or left as viewed in Fig. 2, but the arrangement is such that after the lower end of the handle 10 has been secured in position in the socket 18, the relative bending of the socket to the right or left with relation to the head 11 is limited to a relatively small and unobjectionable amount. In attaining this result it is desirable that the socket 18 have a relatively snug engagement with the handle 10 throughout a substantial distance longitudinally of the handle and to promote such snug engagement, I preferably form lines of stitching 26 through the two layers 14 as shown in Fig. 1, the lines 26 of stitching being formed after the upper end of the absorbent body 12 has been secured in position. These lines 26 of stitching are in the present instance shown as being extended downwardly along the sloping upper edges at 26' and then along the end edges of the head 11 as indicated at 26'', but this is not essential.

When the lower end of the handle 10 is inserted into the socket 18, its lower end is engaged with the upper edge of the absorbent body 12, this upper end edge serving to define the inner or lower end of the socket 18. In the present instance the lower end of the handle has a transverse notch 28 formed therein so that the arms 30 formed on opposite sides of the notch 28 may extend downwardly along the inner surface of the socket for the maximum distance in contact with the inner surface of the fabric of the socket and the head. The handle 10 is held in place

in such a manner with relation to the socket 18 that the fabric 14 in the region indicated at 32 in Fig. 2 is fairly taut, for by this arrangement it is possible to materially restrict the range of lateral bending movement, Fig. 2, of the handle with respect to the head 11. In the form shown in Figs. 1 to 3, the desired connection between the handle and the fabric of the socket is attained by a transverse peg 34 which is extended through aligned openings in the handle and the fabric walls of the socket 18. It will be understood, of course, that where the presence of metal is not objectionable, this connection may be attained by other means such for example as a metallic peg or metallic tacks or nails. With the walls of the socket 18 thus secured to the handle 10 so as to press the lower end of the handle firmly against the upper edge of the absorbent body 12, it will be apparent that lateral bending of the handle 10 in one direction or the other as viewed in Fig. 3 will serve to tension the fabric at the point 32 on one side or the other of the head 11 and this will limit the amount of such bending. Lateral bending of the handle in the other direction with respect to the head 11 that is to the right or left as viewed in Fig. 1 is substantially limited by the form of the head and the manner in which it is associated with the socket 18; and by reason of the engagement of the lower end of the handle 10 with the upper edge of the body 12 above the lines 16 of stitching, any downward force on the handle is transmitted to the beam-like structure afforded in the head 11 by the cooperative action of the fabric, the stitching 16 and the intermediate portions of the body 12.

In Figs. 4 and 5 I have illustrated an alternative construction wherein a different form of fastening means is employed for securing the handle 10 in position in the socket 18. In this embodiment of the invention a relatively strong cord 36 is wound or lashed about the handle 10 as indicated at 38 so that the two ends of the cord 36 may be extended downwardly from the point of fastening 38. One end of the cord 36 is extended into the inside of the socket 18 and is threaded through a lateral opening in the fabric wall of the socket. This end is then extended about the outside of the wall of the socket and is threaded through another opening in the fabric wall of the socket on the opposite side thereof. This end of the cord 36 is then extended upwardly and is connected to the other end of the cord 36 as by a knot 40. Through this arrangement the handle 10 and the socket 18 of the mophead may be secured together with the lower end of the handle 10 drawn tightly against the upper end edge of the absorbent body 12.

From the foregoing description it would be apparent that the present invention enables a mop having a wide and relatively thin head to be produced from the material which is wholly nonmetallic in character, and this end is attained in a manner which requires the use of a minimum length of string or other absorbent material. It will also be evident that this invention enables the wide and relatively thin head of the mop to be formed from a textile fabric such as relatively heavy canvas, and the construction and arrangement is such that this textile fabric may also serve to form an upwardly opening socket for the reception of the usual rod-like handle. In accordance with this invention the fabric mophead and the associated fabric securing means or socket are so constructed and so related that

these parts cooperate with each other in maintaining the wide and thin form of the mophead and in maintaining the mophead in substantially the desired relationship to the handle. It will also be evident that the present invention minimizes the material required for the production of mops, and since such materials are nonmetallic in character, the cost of the material and the cost of the manufacturing operations are substantially less than with prior mops of this general character.

Hence, while I have illustrated and described preferred embodiments of my invention, it is to be understood that these are capable of variation and modification and I therefore do not wish to be limited to the precise details set forth, but desire to avail myself of such changes and alterations as fall within the purview of the following claims.

20 I claim:

1. In a mop, an elongated handle having a lower end, an elongated body of absorbent material arranged so as to be relatively wide and thin at one end thereof which constitutes the upper end of the mop, two layers of relatively heavy textile fabric disposed against opposite faces of the upper end of said body, a plurality of spaced rows of stitching extending transversely of said body and extended through said layers of fabric and the intermediate upper end portion of said absorbent body, said layers of textile fabric being extended upwardly beyond said body and being stitched together to afford an upwardly opening socket adapted to snugly receive said lower end of said handle, said handle being inserted into said socket, and means acting between the fabric of said socket and said handle and securing said handle in said socket with said lower end of said handle held firmly against the upper end of said body.

2. In a mop, an elongated handle having a lower end with a transverse downwardly facing notch therein, an elongated body of absorbent material arranged so as to be relatively wide and thin at one end thereof which constitutes the upper end of the mop, two layers of relatively heavy textile fabric disposed against opposite faces of the upper end of said body, a plurality of spaced rows of stitching extended through said layers of fabric and the intermediate upper end portion of said absorbent body, said rows of stitching being extended transversely of said body, said layers of textile fabric being extended upwardly beyond said body and being stitched together to afford an upwardly opening socket adapted to snugly receive said lower end of said handle, said lower end of said handle being inserted into said socket with said notch embracing the upper end edge of said body, and means acting between the fabric of said socket and said handle and securing said handle in said socket with said notched lower end of said handle embracing and held firmly against said upper end edge of said body.

3. In a mop, an elongated handle having a lower end, an elongated body of absorbent material arranged so as to be relatively wide and thin at one end thereof which constitutes the upper end of the mop, two layers of relatively heavy textile fabric disposed against opposite faces of the upper end of said body, a plurality of rows of stitching extended through said layers of fabric and the intermediate upper end portion of said absorbent body, said rows of stitching being extended transversely of said body, said

layers of textile fabric being extended upwardly beyond said body and being stitched together to afford an upwardly opening socket adapted to snugly receive said lower end of said handle, said handle being inserted into said socket and firmly against the upper end edge of said body, and a securing cord acting between the fabric of said socket and said handle and securing said handle in said socket with said lower end of said handle firmly seated against said upper end edge of said layers of fabric and above the uppermost line of said transverse stitching.

4. In a mop, an elongated handle having a lower end, an elongated flexible body of absorbent material arranged so as to be relatively wide and thin at one end thereof which constitutes the upper end of the mop, two layers of relatively heavy textile fabric disposed against opposite faces of the upper end of said body, a plurality of spaced rows of stitching extending transversely of said body and extended through said layers of fabric and the intermediate upper end portion of said absorbent body, said layers of textile fabric being extended upwardly beyond said body and being stitched together to afford an upwardly opening socket adapted to snugly receive said lower end of said handle, said handle being inserted into said socket, and means extending through the fabric of said socket and transversely into said handle and securing said handle in said socket.

5. In a mop, an elongated handle having a lower end, an elongated flexible body of absorbent material arranged so as to be relatively wide and thin at one end thereof which constitutes the upper end of the mop, two layers of relatively heavy textile fabric disposed against opposite faces of the upper end of said body, a plurality of rows of stitching extended transversely of said body and through said layers of fabric and the intermediate upper end portion of said absorbent body to firmly compress said upper end portion between said layers of fabric, said layers of textile fabric being extended upwardly beyond said body and being stitched together to afford an up-

wardly opening socket adapted to snugly receive said lower end of said handle, said handle being inserted into said socket and firmly against the upper end edge of said absorbent body, and fastening means acting between the fabric of said socket and said handle and securing said handle in said socket.

6. In a mop, an elongated body of absorbent material arranged so as to be relatively wide and thin at one end thereof which constitutes the upper end of the mop, two layers of relatively heavy textile fabric respectively disposed against opposite faces of the upper end of said body, a plurality of spaced rows of stitching extended transversely of said body and through said layers of fabric and the intermediate upper end portion of said absorbent body, and said layers of textile fabric being extended upwardly beyond said body and being stitched together to afford an upwardly opening socket the inner end of which is defined by the upper end edge of said absorbent body and in which socket the lower end of a mop handle may be inserted and secured with the lower end of such handle firmly engaged with said upper end edge of said absorbent body.

7. In a mop, an elongated body of absorbent material arranged so as to be relatively wide and thin at one end thereof which constitutes the upper end of the mop, two layers of relatively heavy textile fabric disposed against opposite faces of the upper end of said body, a plurality of spaced rows of stitching extended transversely of said body and through said layers of fabric and the intermediate upper end portion of said absorbent body so as to firmly compress said upper portion along said rows of stitching, and said layers of textile fabric being extended upwardly beyond said body and being stitched together to afford an upwardly opening socket the inner end of which is defined by the upper end edge of said absorbent body and in which socket the lower end of a mop handle may be inserted and secured.

HENRY L. SWEITZ.
